United States Patent Office

Des. 194,215
Patented Dec. 11, 1962

194,215

GAME TARGET

Merrill L. Hassenfeld, Providence, R.I., assignor to Hassenfeld Bros., Inc., Central Falls, R.I., a corporation of Rhode Island

Filed Mar. 26, 1962, Ser. No. 69,499

Term of patent 14 years

(Cl. D34—5)

FIG. 1

FIG. 2

FIG. 1 is a front perspective view of a game target showing my new design;

FIG. 2 is a side perspective view thereof; and

FIG. 3 is a rear perspective view thereof.

I claim:

The ornamental design for a game target, substantially as shown.
